UNITED STATES PATENT OFFICE.

WILLIAM HAEHNEL, OF NEW YORK, N. Y., ASSIGNOR TO CHARLES PALM,
JULIUS FECHTELER, AND CASPER FECHTELER, ALL OF SAME PLACE.

DESIGN FOR ORNAMENTATION OF SEWING-MACHINES.

SPECIFICATION forming part of Design No. 14,335, dated October 2, 1883.

Application filed August 15, 1883. Term of patent 7 years.

To all whom it may concern:

Be it known that I, WILLIAM HAEHNEL, of the city of New York, and county and State of New York, have invented and produced a new and original Design for the Ornamentation of Sewing-Machines, of which the following is a specification.

This invention relates to a new and original design for the ornamentation of sewing-machines and other articles; and it consists in the novel grouping and configuration of figures, hereinafter more fully described.

The accompanying illustrations show in Figures 1 and 2 opposite views of a sewing-machine plate and arm having thereon my new design. Fig. 3 is a side view of the sewing-machine arm; Fig. 4, the opposite side view of said arm, and Fig. 5 a top view of the cloth-plate ornamented according to this invention.

The figure A is a curving vine bearing upon it thistle-like leaves and bead-shaped fruit. This figure extends along one side of the upright of the arm of the sewing machine, and 25 is more clearly shown in Fig. 3.

B is an ornament for the back portion of the side of the sewing-machine arm, and is also a curved vine having thistle-like leaves and bead-like fruit on its tendrils. It is clearly 30 shown in Fig. 3. The front portion of the side of the arm, which is illustrated in Fig. 3, is ornamented by the curved vine C, which also bears thistle-like leaves and bead-like fruit. Between the figures B and C, the words "The 35 Leader," or other words descriptive of the sewing-machine, are or may be inserted. The opposite side of the sewing-machine arm, which is shown in Fig. 4, is at its lower portion ornamented by the figure D, above which 40 is the figure E, both being curved vines having thistle-like leaves and bead-like fruit on their tendrils. The upper part of the sewing-machine arm on this side of the machine is ornamented by the figures F and G, both of 45 which are also curved vines with thistle-like leaves thereon and bead-like fruit, and between the figures F and G may also be the words

"The Leader," or other words describing the style of the machine.

The cloth-plate is ornamented at its front by 50 a figure, H, which is composed of two curving vines, extending in opposite directions and carrying thistle-like leaves and bead-like fruit. Next to the figure H on the cloth-plate are the figures I I, which are also curving vines having 55 thistle-like leaves and bead-like fruit. Next to these are the larger figures J J, which are likewise curved vines carrying thistle-like leaves and bead-like fruit. The back portion of the cloth-plate is ornamented by the figures 60 L L, which are L-shaped curved vines carrying thistle-like leaves and bead-like fruit.

I claim—

1. The design for the ornamentation of a sewing-machine, consisting of the figure A, as 65 shown.
2. The design for the ornamentation of a sewing-machine, consisting of the figure B, as shown.
3. The design for the ornamentation of a 70 sewing-machine, consisting of the figure C, as shown.
4. The design for the ornamentation of a sewing-machine, consisting of the figure D, as shown.
5. The design for the ornamentation of a 75 sewing-machine, consisting of the figure E, as shown.
6. The design for the ornamentation of a sewing-machine, consisting of the figure F, as 80 shown.
7. The design for the ornamentation of a sewing-machine, consisting of the figure G, as shown.
8. The design for the ornamentation of a 85 sewing-machine, consisting of the figure H, as shown.
9. The design for the ornamentation of a sewing-machine, consisting of the figures I I, as shown.
10. The design for the ornamentation of a 90 sewing-machine, consisting of the figures J J, as shown.
11. The design for the ornamentation of a

sewing-machine, consisting of the figures L, L,
as shown.

12. The design for the ornamentation of a
sewing-machine, consisting of the figures A,
5 B, and C, as shown.

13. The design for the ornamentation of a
sewing-machine, consisting of the figures D,
E, F, and G, as shown.

14. The design for the ornamentation of a

sewing-machine, consisting of the figures H, I,
I, J, and L, as shown.

15. The design for the ornamentation of a
sewing-machine, consisting of the figures A,
B, C, D, E, F, G, H, I, J, and L, as shown.

WILLIAM HAEHNE.
